(57) **CLAIM**

The ornamental design for a sanitary towel, as shown and described.

DESCRIPTION

The FIGURE is a top view of a sanitary towel;

The broken lines shown are for illustrative purposes only and form no part of the claimed design.

1 Claim, 1 Drawing Sheet

U.S. Patent

Sep. 22, 2009

US D600,802 S

UNITED STATES PATENT AND TRADEMARK OFFICE
CERTIFICATE OF CORRECTION

PATENT NO. : D600,802 S
APPLICATION NO. : 29/331242
DATED : September 22, 2009
INVENTOR(S) : Lisa June Hood et al.

Page 1 of 1

It is certified that error appears in the above-identified patent and that said Letters Patent is hereby corrected as shown below:

The first line of the "Description" should read as follows:

--The sole FIGURE is a top view of a sanitary towel; showing our new design.--

Signed and Sealed this
First Day of May, 2012
